CLAIM

The ornamental design for a dispenser for playing cards or the like, as shown and described.

DESCRIPTION

FIG. 1 is a perspective view of a dispenser for playing cards or the like showing my new design;

FIG. 2 is a top plan view thereof; and

FIG. 3 is a left side elevational view thereof.

The rear, bottom, and right sides are plain and unornamented.

FIG. 1

FIG. 3
